PRESSURE SWITCH

Norman J. Smith, Medfield, Mass., assignor to
 Smith Control and Instrument Corporation,
 Needham, Mass.; a corporation of Massachusetts

Application April 12, 1946, Serial No. 661,500

14 Claims. (Cl. 200—83)

1

This invention relates to improvements in a pressure switch and more particularly to a pressure switch for opening or closing electrical circuits generally associated with the control and protection of pressure equipment.

In my prior Patent 2,441,725, dated May 18, 1948, for improvements in thermostatic switch, I have shown a switch responsive to temperature. The present application incorporates certain features of my prior disclosure to a pressure switch.

A pressure switch of the type, to which this invention pertains, essentially comprises a casing or housing generally tubular at one end of the casing and a head at the other end containing a means for biasing the cooperable contacts carried within the casing to opened or closed position as desired. The pressure sensitive diaphragm is so connected to the cooperable contacts that a small movement of the diaphragm will produce a relative multiplied movement between the contacts in a direction transverse to the axis of the casing.

A general object of the invention is to provide a compact pressure switch having a greatly multiplied lateral movement of the electrical contacts for a small longitudinal movement of the pressure sensitive diaphragm.

Another object of the invention is to provide a universal pressure switch capable of being adjusted over wide ranges of both pressure and vacuum.

Still another object provides for biasing the electrical contacts in either a normally closed or normally opened position.

A further object allows a normal amount of unrestrained movement of the diaphragm without further movement of the electrical contacts after separation or closure has been effected.

Still further, the invention incorporates a protective feature limiting the travel of the diaphragm to prevent distortion of the internal members when the switch is accidentally subjected to pressures in excess of those specified.

Additional objects and advantages of other improvements will be more readily apparent from the following description of the two preferred embodiments of my invention as disclosed in the attached drawings, in which:

Fig. 1 is a longitudinal sectional view of a pressure switch which may be adjusted to close an electrical circuit on a decrease in pressure applied to the diaphragm or may be adjusted to open an electrical circuit on an increase in pressure applied to the diaphragm;

Fig. 2 is an end view of the switch shown in Fig. 1;

Fig. 3 is a fragmentary longitudinal sectional view of a switch similar to that disclosed in Fig. 1 but showing a modified arrangement of the struts; and

Fig. 4 is a fragmentary longitudinal sectional view showing a further modification of the switch which may be adjusted to close an electrical circuit on an increase in pressure applied to the diaphragm or to open an electrical circuit on a decrease in pressure applied to the diaphragm.

Referring to Fig. 1, there is shown a casing or housing 10 having a pressure sensitive diaphragm 12 retained in operable alignment with the bore 14 of housing 10 by a flanged coupling 16 and screws 18. The diaphragm 12 constitutes a corrugated thin metallic plate 20 retained by a stud or rivet 22 between the beveled washers 24 and 26, seatable against the shoulders 28 and 30 when excess pressure or vacuum is applied to the diaphragm 12. On the inner side of the diaphragm 12 is mounted a strut 32 having an extension 34 on which a clip 36 carrying contact 38 is fastened. The contact 38 is spaced from electrical contact with the clip 36 by insulation 40. The strut 32 extends from the diaphragm 12 toward the opposite end of the casing 10 and is reversely bent near said upper end to form a U-shaped member comprising an arc or bow 42 intermediate substantially parallel legs 44 and 46. The U-shaped member 42—44—46 need not be so shaped since it may be formed as shown at 102 in Fig. 3 as I later describe on some other page may be employed, it being understood that this member constitutes a substantially rigid compression or tension member to produce the desired leverage.

40 Threaded into the head 48, which is affixed to the casing 10 by screws 50, is an adjusting bolt or screw 52 having a relatively coarsely threaded external section 54 and an internal socket receiving a finely threaded section 56 of stud 58, the stud 58 being rigidly secured to the resilient dog 60 which is an integral part of the head 48. Turning adjusting bolt 54 in a clockwise direction will cause the bolt 52 to thread into the head 48 and the stud 58 to thread into the bolt 52 at a slower rate which will cause the stud 58 to move toward the diaphragm 12 to deflect the dog 60.

45 A leaf spring 62 is attached to the inner side of the dog 60 and extends towards the diaphragm 12, near which a clip 64 carrying a contact 66

is fastened and is separated from the leaf spring 62 by insulation 68. To contacts 38 and 66 are attached flexible cables 70 and 72 which emerge from the casing 10 through the grommet 14. The leaf spring 62 has a pair of slots 76 and 78 receiving pins 80 and 82 which slidably retain the leg 46 of strut 32 against the leaf spring 62. The pin 80 also provides a rigid reinforcement for the arc 42 by retaining tubular spacer 84 in a fixed position intermediate the legs 44 and 46.

A clockwise turning of the adjusting bolt 52 will cause the stud 58 to move towards the diaphragm 12 and deflect the dog 60 inwardly of the casing and move the leaf spring 62 until the lost motion of slots 76 and 78 is taken up and the thrust will deflect the leaf spring 62 in a direction to effect a separation of the contact 66 from the contact 38. An outward movement of the diaphragm 12, as will result from a decrease in pressure, will cause tension in the leg 44 of strut 32 and a movement of the tubular spacer 84 which acts as a short lever arm to allow the leaf spring 62 which acts as a long lever arm to spring the electrical contact 66 into engagement with the contact 38. After the contacts 38 and 66 have been closed, a further outward movement of the diaphragm 12 will merely allow the pins 80 and 82 to freely slide in the slots 76 and 78, the engagement of the contacts 38 and 66 being maintained by the spring action imposed on the leaf spring 62 by the action of the tubular spacer or short lever arm 84. An excessive outward movement of the diaphragm will result in the beveled washer 24 abutting against the shoulder 28 before the pins 80 and 82 travel the entire length of their respective slots 76 and 78.

To bias the electrical contacts 38 and 66 in a closed position so that they will open on an increase in pressure, the adjusting bolt 54 must be turned in a counter clockwise direction until the inner ends of the slots 76 and 78 have engaged the pins 80 and 82. An increase in pressure against the diaphragm will then result in a compression of the leg 44 which will cause the tubular spacer or short lever arm 84 to pivot and cause the leaf spring or long lever arm 62 to deflect, so that the contact 66 will tend to separate from the contact 38. Here again, after separation of the contacts further movement of the diaphragm will merely cause the pins 80 and 82 to freely slide in the slots 76 and 78 until the beveled washer 26 abuts against the shoulder 30 and stops further movement, as would be the case when an excessive pressure is applied against the diaphragm 12.

Referring to Fig. 3, there is shown another embodiment of the invention in which the same reference numerals are used in so far as possible, since the construction is quite similar to that in Fig. 2. In this arrangement the U-shaped strut 32 is replaced by the strut 100 having angularly disposed section 102 terminating against strip 104 which is held against the leaf spring 62 by the pins 80 and 82 slidably received in the slots 76 and 78. The upper end of the leaf spring 62 is non-rotatably held to the clevis 106 by pin 108 having one end slidably received by a longitudinal slot 110 in stud 112 which is fastened to the head 48 by a rivet 114. The threaded section 116 of the clevis 106 is received by the adjusting bolt 52 which is in turn threaded into the head 48 as in Fig. 1. Longitudinal movement of the leaf spring 62 is permitted by the pin 108 sliding in the slot 110 without rotation of the clevis 106 when the adjusting bolt 52 is turned.

The switch as so far described is capable of adjustment to operate on an increase in pressure or a decrease in pressure it being understood that it could also operate under vacuum by an increase or decrease in the vacuum. In one adjustment, the contacts are initially biased to closed position and upon an increase in the pressure on the diaphragm, the contacts will be opened thereby opening the electrical circuit. The switch may also be adjusted to bias the contacts to opened position whereby a decrease in pressure applied to the diaphragm will close the contacts and complete the electrical contact. It may be desired to obtain just the reverse operation; that is, a switch which will close the electrical circuit on an increase in pressure or will open the electrical circuit on a decrease in pressure. To carry out this function, the switch may be designed as shown in Fig. 4 in which the U-shaped member comprising the legs 44 and 46 is the same as in Fig. 1 but a contact 120 is fastened to the leg 44 by the clip 122 and separated therefrom by insulation 124. The member 44 is connected to the diaphragm by the rivet 22. The leg 46 of the U-shaped member is attached to the leaf spring 62 as in Fig. 1 and carries a contact 126 fastened by clip 128 and insulated from the part 62 by insulation 130. It will be evident that in this arrangement the adjusting screw 54 must be turned in to bias the contacts to closed position while moving the screw outward will bias the contacts to opened position. After contacts are initially biased to closed position, then a decrease in pressure will open the contacts; whereas if the contacts are initially biased to opened position an increase in pressure will close the contacts.

The switch as shown in Fig. 1 may be adjusted by the screw 54 to bias the leaf spring of strut 62 and initially close the contacts. That is, the leaf spring 62 will be sprung adjacent its mounting on the finger 60 so that the contacts are held closed and the strut structure from the diaphragm will be placed under tension whereby an increase in pressure on the diaphragm is required to relieve the tension and permit the contacts to open. If, on the other hand, the adjusting screw 54 is initially turned to bias the leaf spring or strut 62 in a direction to open the contacts, the strut structure from the diaphragm will be placed under compression and decrease in pressure on the diaphragm will be required to relieve the compression and permit the contacts to close. The modified construction of the switch as in Fig. 4 will similarly be adjusted to tension or compression but the action will be just the reverse.

While I have shown and described preferred embodiments of my invention, I do not wish to be limited thereto as the invention is capable of modification within the scope of the appended claims.

I claim:

1. In a pressure switch, a housing, a pressure sensitive diaphragm, a resilient leaf spring mounted in said housing, a contact carried by the free end of said leaf spring, a contact adapted to be engaged by said first mentioned contact, a member having one end mounted on said diaphragm and means engaging the other end of said member with said leaf spring for causing a relative movement between said contacts by a variation in the pressure upon the diaphragm.

2. In a pressure switch, a housing, a pressure sensitive diaphragm, a relatively short strut

mounted on said diaphragm, a contact carried by said strut, a relatively long strut forming a U-shaped member having one leg mounted on said diaphragm and a reversely bent second leg resiliently attached to said housing, a contact carried by the long strut cooperable with the first mentioned contact, whereby a pressure actuated movement of said diaphragm will cause a relative multiplied movement between said contacts.

3. In a pressure switch, a housing having internal shoulders, a pressure sensitive diaphragm constituting a sheet of resilient material inserted between a pair of abutments, the abutments forming a double stop seatable against said shoulders within said housing, a relatively short strut mounted on said diaphragm, a contact carried by said strut, a relatively long strut forming a U-shaped member having one leg mounted on said diaphragm and a second leg resiliently attached to said housing, a contact carried by the long strut cooperable with the first mentioned contact, whereby the abutments of said diaphragm will seat against the shoulders of said housing to prevent damage from excessive pressure or vacuum.

4. In a pressure switch, a casing having a head at one end, a pressure sensitive diaphragm mounted at the other end, a relatively short strut mounted on said diaphragm and extending toward the head of said casing, a contact carried by said strut, a relatively long strut forming a resilient U-shaped member composed of one leg mounted on said diaphragm which extends towards said head and a reversely bent second leg which projects back towards said diaphragm, a contact carried by the long strut cooperable with the first mentioned contact, a resilient strip having one end adjustably mounted on the head of said casing and the other end engageable near said head with the reversely bent leg of said long strut, said long strut being initially biased toward separation of said contacts by engagement of said resilient strip with said reversely bent leg and means for longitudinally adjusting the mounting of said resilient strip with respect to said head to cause said contacts to close, whereby said contacts will open at a predetermined increased pressure on the diaphragm.

5. In a pressure switch, a casing having a head at one end, a pressure sensitive diaphragm mounted at the other end, a relatively short strut mounted on said diaphragm and extending toward the head of said casing, a contact carried by said strut, a relatively long strut forming a resilient U-shaped member composed of one leg mounted on said diaphragm which extends towards said head and a reversely bent second leg which projects back towards said diaphragm, a contact carried by the longer strut cooperable with the first mentioned contact, a resilient strip having one end adjustably mounted on the head of said casing and the other end engageable near said head with the reversely bent leg of said longer strut, said longer strut being initially biased toward closure of said contacts by engagement of said resilient strip with said reversely bent leg, means for longitudinally adjusting the mounting of said resilient strip with respect to said head to cause said contacts to open, whereby said contacts will close at a predetermined reduced pressure on the diaphragm.

6. A pressure switch for an electrical circuit comprising a casing having a head at one end, a pressure sensitive diaphragm mounted at the other end, a relatively short strut and a relatively

long U-shaped strut mounted on said diaphragm, a pair of cooperable contacts carried by said struts near said diaphragm, a resilient strip having a slot in one end and having the other end mounted on the head of said casing, means received by said slot for slidably retaining said resilient strip to said U-shaped strut near said head, whereby a longitudinal movement of said diaphragm will produce a multiplied lateral movement between said contacts up to a predetermined point after which further lateral movement ceases as said means is then free to move with respect to said slot.

7. In a pressure switch, a housing, a pressure sensitive diaphragm, a substantially rigid L-shaped member having relatively long and short lever arms, means resiliently mounting said member within said housing, a contact carried by the long lever arm of said member, a contact adapted to be engaged by said first mentioned contact and means connecting said diaphragm to the short lever arm of said member for causing relative movement between said contacts at a predetermined pressure.

8. In a pressure switch, a casing having a head, a resilient dog integral with said head, a pressure sensitive diaphragm, a pair of contact carrying struts movable by said diaphragm to cause a relative movement of said contacts, means connecting one of said struts to said dog, an adjusting screw threaded into said head, a second screw rigidly mounted on said dog and threaded into said adjusting screw, said adjusting screw having relatively coarse external threads and fine internal threads to engage the second screw whereby an inward turning of said adjusting screw will result in a slower inward movement of said second screw to cause a precise deflection of said dog and a resulting biased position of said contacts.

9. In a pressure switch, a casing having a head, a pressure sensitive diaphragm, a pair of contact carrying struts movable by said diaphragm to cause relative movement between said contacts, an adjusting screw threaded into said head, a second screw threaded into said adjusting screw, means connecting one of said struts to said second screw and means mounted on said head for holding said second screw against rotation when biasing said contacts.

10. In a pressure switch, a pressure sensitive diaphragm, a first strut movable by said diaphragm, a second strut resiliently mounted at one end and forming a long lever arm, means connecting the first strut to said second strut near the resiliently mounted end thereof whereby the force transmitted through said first strut by movement of the diaphragm is applied at an angle to said second strut to form in effect a short lever arm, a first electrical contact carried by said second strut at its end opposite to the resiliently mounted end and a second electrical contact cooperable with said first contact.

11. In a pressure switch, a pressure sensitive diaphragm, a first strut movable by said diaphragm, a second strut resiliently mounted at one end and forming a long lever arm, means connecting the first strut to said second strut near the resiliently mounted end thereof whereby the force transmitted through said first strut by movement of the diaphragm is applied at an angle to said second strut to form in effect a short lever arm, a first electrical contact carried by said second strut at its end opposite to the resiliently mounted end and a second electrical contact cooperable with said first contact, and

means for biasing the second strut to initially close the contacts whereby the contacts will open at a desired degree of the pressure.

12. In a pressure switch, a pressure sensitive diaphragm, a first strut movable by said diaphragm, a second strut resiliently mounted at one end and forming a long lever arm, means connecting the first strut to said second strut near the resiliently mounted end thereof whereby the force transmitted through said first strut by movement of the diaphragm is applied at an angle to said second strut to form in effect a short lever arm, a first electrical contact carried by said second strut at its end opposite to the resiliently mounted end and a second electrical contact cooperable with said first contact, and means for biasing the second strut to open the contacts whereby the contacts will close at a desired degree of pressure.

13. In a pressure switch, a pressure sensitive diaphragm, a first strut movable by said diaphragm, a second strut resiliently mounted at one end and forming a long lever arm, means connecting the first strut to said second strut near the resiliently mounted end thereof whereby the force transmitted through said first strut by movement of the diaphragm is applied at an angle to said second strut to form in effect a short lever arm, a first electrical contact carried by said second strut at its end opposite to the resiliently mounted end and a second electrical contact cooperable with said first contact, and means for biasing the second strut to place the the

first strut under compression whereby decrease in pressure on the diaphragm will relieve the compression and cause relative movement between the contacts.

- 5 14. In a pressure switch, a pressure sensitive diaphragm, a first strut movable by said diaphragm, a second strut resiliently mounted at one end and forming a long lever arm, means connecting the first strut to said second strut near the resiliently mounted end thereof whereby the force transmitted through said first strut by movement of the diaphragm is applied at an angle to said second strut to form in effect a short lever arm, a first electrical contact carried by said second strut at its end opposite to the resiliently mounted end and a second electrical contact cooperable with said first contact, means for biasing the second strut to place the first strut under tension whereby an increase in pressure upon the diaphragm will relieve the tension and cause relative movement between the contacts.
